UNITED STATES PATENT OFFICE.

ROBERT F. BRACKE, OF CHICAGO, ILLINOIS, ASSIGNOR TO CURTIS B. CAMP, TRUSTEE, OF GLENCOE, ILLINOIS.

FUEL-FEED SYSTEM FOR MOTOR VEHICLES.

Original application filed April 13, 1923, Serial No. 631,822. Divided and this application filed October 22, 1926. Serial No. 143,364.

My invention relates to fuel feed systems for motor vehicles, and has for its general object the provision of improved means for lifting fuel from the fuel supply tank to a carburetor mounted above the tank.

This application is a divisional part of my co-pending application for patent on suction producing means for fuel feed systems, Serial No. 631,822, filed April 13, 1923.

10 In the accompanying drawings:

Figure 1 is a side elevational view of an automobile chassis showing the system of my invention;

15 Figure 2 is an end elevational view of the vortex ejector employed in the system of my invention;

20 Figure 3 is a vertical cross sectional view taken along the line 3—3 of Figure 2, looking in the direction indicated by the arrows; and

Figure 4 is a fragmentary cross sectional view showing a modified form of ejector nozzle.

25 Similar characters of reference refer to similar parts through the several drawings.

Referring first to Figure 1, 5 designates an automobile frame, 6 an engine mounted therein, 7 the radiator and 8 the fuel supply tank mounted at the rear of the car and 30 below the carburetor 9. Mounted above the carburetor 9 is the usual form of vacuum feed tank 10 arranged to draw fuel from the tank 8 through the pipe 11. From the tank 10 the fuel is permitted to flow by 35 gravity to the carburetor 9. All of the foregoing is well-known construction and needs no further explanation.

40 My invention relates to the means for producing the suction or reduction in pressure necessary in the operation of the vacuum feed tank and comprises the use of a vortex ejector in the water-circulating system of the engine. In Figure 1, 12 designates a vortex ejector forming part of 45 the water-circulating system extending between the engine water jacket and the radiator. As shown in Figures 2 and 3 this ejector is made up of a casing 13 arranged to provide a vortex chamber 14, a 50 water inlet 15 tangent to the chamber 14, and a water outlet 16 concentric with the chamber. Extending into the chamber 14 and concentric therewith is an ejector or nozzle 17 arranged for a pipe fitting at 18

for the purpose of communicating the suction produced at the nozzle to the vacuum feed tank, as shown at 19 in Figure 1.

I have discovered that by placing the ejector in the water-cooling system where it leaves the engine, all possibility of the injection of air within the water jackets of the engine is prevented. The presence of air in the engine jackets of a water-cooling system gives rise to rapid oxidation of the jacket walls and, therefore, the accumulation of scale which eventually clogs the system, should it find its way to the radiator tubes. There is, also, the disadvantage caused by the formation of air pockets and their tendency to reduce the efficiency of the cooling system.

In the operation of the device, the cooling water is forced tangentially into the chamber 14 and, because of the centrifugal force produced by the vortex or whirlpool action of the water, produces a high suction at the nozzle which is used to lift fuel as described.

55 In Figure 4 I have shown a modified form of nozzle 17' with suction holes radiating from the center.

Having thus described my invention, what I claim is new and desire to secure by Letters Patent of the United States is:

1. A fuel feed system for motor vehicles, comprising in combination an engine, a carburetor therefor, a fuel feed tank mounted above the carburetor and arranged to feed fuel thereto, a fuel supply tank below the carburetor and communicating with the feed tank, a water circulating system for the engine, and an ejector in the circulating system located so as to receive the water as it leaves the engine for producing a suction in the feed tank.

85 2. A fuel feed system for motor vehicles comprising an engine, a carburetor therefor, a vacuum feed tank mounted above the carburetor and arranged to feed fuel thereto, a supply tank below the carburetor and communicating with the fuel feed tank, a water circulating system for the engine including a vortex chamber arranged to receive the water as it leaves the engine, and a nozzle in the chamber connected to the fuel feed tank for the purpose of communicating a suction at the vortex to the fuel feed tank.

100 105 3. A fuel feed system for motor vehicles comprising in combination an engine, a car-

buretor therefor, a vacuum feed tank mounted above the carburetor and arranged to feed fuel thereto by gravity, a fuel supply tank below the carburetor and communicating with the feed tank, a water-circulating system for the engine, and an ejector in the circulating system located so as to receive the water as it leaves the engine and con-

nected with the fuel feed tank above the level of fuel therein for producing suction in said tank, whereby fuel is lifted from the main supply tank to the vacuum feed tank.

In witness whereof, I hereunto subscribe my name this 19th day of October, 1926.

ROBERT F. BRACKE.
